UNITED STATES PATENT OFFICE.

WENSEL MORAVA, OF CHICAGO, ILLINOIS.

ELECTRIC RIVETER.

1,321,136.

Specification of Letters Patent. Patented Nov. 11, 1919.

Application filed September 22, 1917. Serial No. 192,647.

To all whom it may concern:

Be it known that I, WENSEL MORAVA, a citizen of the United States, residing at Chicago, in the county of Cook and State of Illinois, have invented a certain new and useful Improvement in Electric Riveters, of which the following is a specification.

My invention relates to improvements in electric riveting machines and has for one object to provide an arrangement whereby by the mere manipulation of the lever the plunger may be worked back and forth against the work just as it can be worked when a steam or air riveter is used. Another object is for easily and conveniently manipulating the driving mechanism and associated parts. Another object of my invention is to provide a riveter which will be automatic in its operation in exactly the same sense as steam or air riveter is automatic that is to say in which one movement of the control lever by the operator will be sufficient to completely control all the operating parts.

My invention is illustrated more or less diagrammatically in the accompanying drawings wherein—

Figure 1 is a side elevation;

Fig. 2 is a section on an enlarged scale on the line 2—2 of Fig. 1;

Fig. 3 is a section on the line 3—3 of Fig. 2;

Fig. 4 is a section on the line 4—4 of Fig. 2;

Fig. 5 is a longitudinal section of the planetary gear;

Fig. 6 is a section on the line 6—6 of Fig. 5.

Like parts are indicated by like letters throughout the several figures.

Mechanical details.

A is the usual type of rigid jaw construction, on the lower member of which is mounted an anvil bar A¹. The upper member or part of the jaw carries a guide head A², in which is slidably mounted the plunger A³ carrying a screw threaded adjustment therein and a driving bar A⁴ with a rivet forming head A⁵ in opposition to the end of the anvil bar A¹.

B¹ is a bracket extending rearwardly from

the jaw A carrying an electric motor B² which drives the shaft B⁴. The shaft and motor are always in rotation when the riveting machine is being used. B⁵ is a bearing for the front end of the shaft supported on the bracket B⁶.

C is a sleeve rotatably mounted on the shaft B⁴ and in turn rotatably mounted in bearing sleeves C¹ C² in a housing C³ on the jaw A. The central portion of the sleeve C carries a driving worm C⁵ provided with thrust ball bearings indicated. This worm is in mesh with the worm wheel C⁷ in the casing C⁸ supported on the housing C³. The worm wheel is mounted on and drives a shaft C⁹.

Crank disks D D are mounted one at each end of the shaft C⁹ and driving links D¹ are pivoted one to each of said disks. These links are pivoted on a knuckle pin D² which pin is supported in the tension toggle links D³ pivoted one at either side of the head A². D⁴ is a thrust pin pivoted on the knuckle pin intermediate its ends and rotatably engaging the upper end of the plunger A³ there being a cylindrical bearing provided as indicated.

E is the driving portion of an electromagnetic clutch. It is rigidly mounted on and always rotates with the shaft B⁴ and is provided with slip-rings E¹ E² whereby electric current is supplied to the clutch. E³ is the driven portion of this clutch and it is rigidly mounted on the sleeve C so as to always rotate with it.

F is a planetary gear or transmission housing containing a planetary gear, the member F¹⁰ of which is secured against rotation in relation to the shaft B⁴. By its engagement with the pinions F¹¹ it rotates the sleeve C by rotating its enlarged end or sleeve C¹⁰ as illustrated in Fig. 5. The sleeve C is then rotated in the same direction as the shaft B⁴.

The pinions F¹¹ are rotatably mounted on pins F¹², set in the brake drum F⁶ which normally revolves with the planetary gear. The brake drum, when the brake band F⁸ is tightened upon it by means of the hand lever F⁹, being then held against rotation, prevents the rotation of the pinions F¹¹ about the axis of rotation of B⁴. Their rotation

on the pins F^{12} continues, and the gear C^{10} with the sleeve C is thus rotated in reverse direction to the rotation of B^4 .

Electric details.

5 I have shown the electric details in more or less diagrammatic form sufficient, however, to indicate in general terms what happens.

10 I I^1 are conductors leading to any suitable source of power. I^2 is a two point switch controlling said conductors. I^3 is a conductor leading from one point of such switch to the motor. I^4 is a conductor leading from the other point to a solenoid I^5 . I^6 is a conductor leading from the solenoid to the motor. When the switch is closed the current passes through the motor and through the solenoid and the shaft is rotated. 15 20 This is the normal operating condition. The conductors I I^1 also communicate with terminals I^7 I^8 supported on the member A. Knife switch members I^9 I^{10} are mounted on the lever F^9 in opposition to the members I^7 I^8 .

25 K is a conductor leading from the member I^9 to the brush K^1 in engagement with the slip ring E^1 . K^2 is a brush engaging the slip ring E^2 and K^3 is a conductor leading therefrom to a normally closed switch K^4 . K^5 is a conductor leading from this closed switch K^4 to the terminal member I^{10} thus closing the electric circuit through the clutch. K^6 K^7 are insulation buttons 30 35 diametrically opposed on one of the members D adapted to engage the finger K^8 on the switch K^4 to break the clutch circuit at each half revolution of the crank disk D. K^9 is a shunt circuit extending across the 40 switch K^4 adapted to be closed by the operator who presses on the thumb piece K^{10} to close the switch K^{11} .

45 The circuit is also broken intermediate the ends of the conductor K by a switch L which is controlled by the plunger L^1 of the solenoid I^5 , which holds it against the compressed spring L^2 . This plunger also serves as a latch to hold the lever F^9 against rotation resisting the spring L^2 which tends 50 yieldingly to thrust it away the parts being so arranged that when the current in the motor exceeds a certain predetermined point the solenoid plunger will be withdrawn, the clutch circuit will be broken at the point L and the lever will then be thrust out by the spring thus breaking the circuit also at I^7 I^8 . Any suitable means not shown 55 may be used to hold the plunger L^1 in extended position while the solenoid circuit 60 is broken.

The use and operation of my invention are as follows:—

65 When the motor circuit is closed as indicated the motor rotates, the drive shaft rotates with it. The main control lever will

normally be in open position and the crank disk will normally be in such position that the insulation pins on it break the clutch circuit. The operator will then push in on the lever to close the clutch circuit at the 70 two point switch on the lever. He then positions his work and presses on the button on the lever handle. This short circuits the crank disk control switch and starts rotation of the crank disk. Immediately 75 the insulation button goes out of action and the clutch circuit is closed across the spring held switch the operator may release the button. The crank disk will rotate and the plunger will descend until it reaches the end 80 of its excursion when the button on the crank disk will again break the clutch circuit. The operator then touches the button on the lever and the crank disk makes a second half revolution releasing the work. 85

If, however, the load is so great that there is danger to the motor and associated parts there will be a surge of current in the motor circuit and the solenoid therein will be excited. This will cause the solenoid to draw 90 back on the plunger and first break the clutch circuit. It then releases the latch holding the lever in against the spring and the lever will fly out, work will stop, the operator will then pull out farther on the 95 lever to mechanically operate the planetary transmission to reverse the drive. As soon as the plunger has been withdrawn the operator can drive in the lever again closing the circuit and causing the forward movement. If this is not enough to do the work he can pull out on the lever again reverse the rivet driving mechanism and start it again. In other words, by pumping the lever back and forth the operator can move 100 the plunger back and forth, can pound on the rivet and in this way be sure of driving it because, of course, since the parts are relatively heavy even any slight movement will store a very considerable amount of 110 energy such as will under ordinary circumstances be sufficient to drive the rivet. This operation takes place without manipulation of the button on the lever because that button is needed to bridge the gap only when 115 the crank disk is at its innermost or its outermost position, that is to say, manipulation of the lever is needed to cause movement of the plunger only at the two ends of its stroke.

120 The circuit breaker is made up of a switch plunger carrying a contact section adapted to engage a fixed contact member. It is normally thrust in one direction by a spring and locked against movement by a latch 125 on the end of the solenoid plunger. When the overload in the motor circuit exceeds a certain predetermined point the plunger is withdrawn from the latch and the spring acting on the plunger breaks the circuit. 130

The operator then manipulates the master lever pulling it out to first open the main switch and break the main clutch circuit in another place. He pulls it out farther 5 to operate the reverse.

I claim:

1. An electric riveting machine comprising a motor, a rivet driving plunger, a drive wheel permanently connected thereto, a 10 clutch and a reversing gear interposed between the motor and the drive wheel and a controlling lever adapted when moved in one direction to throw the reversing gear into operation and when moved in the other 15 direction to throw the clutch into operation, a mechanical connection between the lever and the reversing gear and an electrical connection between the lever and the clutch.

2. An electric riveting machine comprising a motor, a rivet driving plunger, a drive wheel permanently connected thereto, a 20 clutch and a reversing gear interposed between the motor and the drive wheel and a controlling lever adapted when moved in one direction to throw the reversing gear 25 into operation and when moved in the other direction to throw the clutch into operation, yielding means tending to force the controlling lever out of the clutch operating position, locking means for keeping said yielding means in inoperative position, and means responsive to an overload on the motor for releasing said yielding means.

3. An electric riveting machine comprising a motor, a rivet driving plunger, a drive wheel permanently connected thereto, a 35 clutch and a reversing gear interposed between the motor and the drive wheel and a controlling lever adapted when moved in one direction to throw the reversing gear 40 into operation and when moved in the other direction to throw the clutch into operation, a mechanical connection between the lever and the reversing gear and an electrical connection 45 between the lever and the clutch, yielding means tending to force the controlling lever out of the clutch operating position, locking means for keeping said yielding means in inoperative position, and means 50 responsive to an overload on the motor for releasing said yielding means.

4. An electric riveting machine comprising a motor, a rivet driving plunger, a drive wheel permanently connected thereto, a 55 clutch and a reversing gear interposed between the motor and the drive wheel and a controlling lever adapted when moved in one direction to throw the reversing gear 60 into operation and when moved in the other direction to throw the clutch into operation, yielding means tending to force the controlling lever out of the clutch operating position, locking means for keeping said yielding means in inoperative position, and 65 means responsive to an overload on the mo-

tor for releasing said yielding means, said releasing means comprising a solenoid in series with the motor circuit and a plunger controlled by the solenoid.

5. An electric riveting machine comprising a motor, a rivet driving plunger, a drive wheel permanently connected thereto, a clutch and a reversing gear interposed between the motor and the drive wheel and a controlling lever adapted when moved in one direction to throw the reversing gear 70 into operation and when moved in the other direction to throw the clutch into operation, a mechanical connection between the lever and the reversing gear and an electrical connection between the lever and the clutch, yielding means tending to force the controlling lever out of the clutch operating position, locking means for keeping said yielding means in inoperative position, and means 75 responsive to an overload on the motor for releasing said yielding means, said releasing means comprising a solenoid in series with the motor circuit and a plunger controlled by the solenoid.

6. An electric riveting machine comprising a motor, a rivet driving plunger, a drive wheel permanently connected thereto, a clutch and a reversing gear interposed between the motor and the drive wheel and a controlling lever adapted when moved in one direction to throw the reversing gear 80 into operation and when moved in the other direction to throw the clutch into operation, a mechanical connection between the lever and the reversing gear and an electrical connection between the lever and the clutch, yielding means tending to force the controlling lever out of the clutch operating position, locking means for keeping said yielding means in inoperative position, and means 85 responsive to an overload on the motor for releasing said yielding means, said releasing means comprising a solenoid in series with the motor circuit and a plunger controlled by the solenoid.

7. An electric riveting machine comprising a motor, a rivet driving plunger, a drive wheel permanently connected thereto, a clutch and a reversing gear interposed between the motor and the drive wheel and a controlling lever adapted when moved in one direction to throw the reversing gear 90 into operation and when moved in the other direction to throw the clutch into operation, a mechanical connection between the lever and the reversing gear and an electrical connection between the lever and the clutch, a switch in the clutch circuit separate from the lever and means responsive to an overload in the motor circuit for opening said switch.

8. An electric riveting machine comprising a motor, a rivet driving plunger, a drive wheel permanently connected thereto, a 100 clutch and a reversing gear interposed between the motor and the drive wheel and a controlling lever adapted when moved in one direction to throw the reversing gear 105 into operation and when moved in the other direction to throw the clutch into operation, a mechanical connection between the lever and the reversing gear and an electrical connection between the lever and the clutch, a switch in the clutch circuit separate from the lever and means responsive to an overload in the motor circuit for opening said switch, means tending normally to throw the lever out of the clutch operating position, means resisting said lever throwing means, the switch breaking means adapted 115 simultaneously to release the lever throwing means.

8. An electric riveting machine comprising a motor, a rivet driving plunger, a drive wheel permanently connected thereto, a 120 clutch and a reversing gear interposed between the motor and the drive wheel and a controlling lever adapted when moved in one direction to throw the reversing gear 125 into operation and when moved in the other direction to throw the clutch into operation, a mechanical connection between the lever and the reversing gear and an electrical connection between the lever and the clutch, a switch in the clutch circuit separate from the lever and means responsive to an overload in the motor circuit for opening said switch, means tending normally to throw the lever out of the clutch operating position, means resisting said lever throwing means, the switch breaking means adapted simultaneously to release the lever throwing means.

electrical clutch interposed between the motor and the drive wheel and a mechanical reversing gear interposed between them, a lever adapted to control the mechanical reversing gear, a switch mounted on the lever controlling the clutch circuit, and an auxiliary switch controlling the clutch circuit independent of the lever.

9. An electric riveting machine comprising a motor, a rivet driving plunger, a drive wheel permanently connected thereto, an electrical clutch interposed between the motor and the drive wheel and a mechanical reversing gear interposed between them, a lever adapted to control the mechanical reversing gear, a switch mounted on the lever controlling the clutch circuit, an auxiliary switch controlling the clutch circuit separate from the lever, and means for opening said auxiliary switch independent of the lever and lever controlled means for closing it.

10. An electric riveting machine comprising a motor, a rivet driving plunger, a drive wheel permanently connected thereto, an electrical clutch interposed between the motor and the drive wheel and a mechanical reversing gear interposed between them, a lever adapted to control the mechanical reversing gear, a switch mounted on the lever controlling the clutch circuit, an auxiliary switch controlling the clutch circuit separate from the lever, yielding means tending normally to throw the lever into a neutral position to open the switch, locking means for holding the yielding means in the closed position with the switch closed.

11. An electric riveting machine comprising a motor, a rivet driving plunger, a drive wheel permanently connected thereto, an electrical clutch interposed between the motor and the drive wheel and a mechanical reversing gear interposed between them, a lever adapted to control the mechanical reversing gear, a switch mounted on the lever controlling the clutch circuit, an auxiliary switch controlling the clutch circuit separate from the lever, yielding means tending normally to throw the lever into a neutral position to open the switch, locking means for holding the yielding means in the closed position with the switch closed, and automatic means responsive to the condition of the motor circuit for releasing the locking means.

12. An electric riveting machine comprising a motor, a rivet driving plunger, a drive wheel permanently connected thereto, an electrical clutch interposed between the motor and the drive wheel and a mechanical reversing gear interposed between them, a lever adapted to control the mechanical reversing gear, a switch mounted on the lever controlling the clutch circuit, an auxiliary switch controlling the clutch circuit separate

from the lever, yielding means tending normally to throw the lever into a neutral position to open the switch, locking means for holding the yielding means in the closed position with the switch closed, comprising a solenoid and plunger adapted to control the auxiliary switch and to release the yielding means responsive to an overload on the motor circuit.

13. An electric riveting machine comprising a motor, a rivet driving plunger, a drive wheel permanently connected thereto, an electrical clutch interposed between the motor and the drive wheel and a mechanical reversing gear interposed between them, a lever adapted to control the mechanical reversing gear, a switch mounted on the lever controlling the clutch circuit, a circuit breaking apparatus adapted to break the clutch circuit responsive to an overload in the motor circuit comprising a solenoid and a circuit breaking spring operating plunger and means responsive to the movement of the lever after the switch has been broken thereby closing the circuit breaking switch and setting it ready for further operation.

14. In an electric riveting machine comprising a motor, a rivet driving plunger, a drive wheel permanently connected thereto, an electric clutch and a mechanical reversing gear interposed between the motor and the drive wheel, a controlling lever adapted mechanically to control the reversing gear, and a switch on the lever adapted to control the electric clutch.

15. In an electric riveting machine comprising a motor, a rivet driving plunger, a drive wheel permanently connected thereto, an electric clutch and a mechanical reversing gear interposed between the motor and the drive wheel, a controlling lever adapted mechanically to control the reversing gear, and a switch on the lever adapted to control the electric clutch, said switch acting independently of the position of the lever.

16. In an electric riveting machine comprising a motor, a rivet driving plunger, a drive wheel permanently connected thereto, an electric clutch and a mechanical reversing gear interposed between the motor and the drive wheel, a controlling lever adapted mechanically to control the reversing gear when rotated in one direction, said lever bearing switch contacts adapted when the lever is rotated in the opposite direction to close the electric clutch circuit, and a switch on the lever adapted to close the electric clutch circuit, said switch acting independently of the position of the lever.

17. An electric riveting machine comprising a motor, a rivet driving plunger, a drive wheel permanently connected thereto, a clutch and a reversing gear interposed between the motor and the drive wheel and a controlling device adapted when moved in

one direction to throw the reversing gear into operation and when moved in the other direction to throw the clutch into operation, a mechanical connection between the lever 5 and the reversing gear and an electrical connection between the lever and the clutch, a switch in the clutch circuit separate from the lever, means normally inoperative for opening said switch, and means responsive to an 10 overload in the motor circuit for making said means operative.

18. An electric riveting machine comprising a motor, a rivet driving plunger, a drive wheel permanently connected thereto, a 15 clutch and a reversing gear interposed between the motor and the drive wheel and a controlling lever adapted when moved in one direction to throw the reversing gear into

operation and when moved in the other direction to throw the clutch into operation, a 20 mechanical connection between the lever and the reversing gear and an electrical connection between the lever and the clutch, a switch in the clutch circuit separate from the lever, yielding means normally locked in inactive position, for opening said switch, and means responsive to an overload in the motor 25 circuit for releasing said yielding means.

In testimony whereof, I affix my signature in the presence of two witnesses this 4th day 30 of September 1917.

WENSEL MORAVA.
